UNITED STATES PATENT OFFICE.

BERNARD H. SKELLY, OF BRIDGEPORT, CONNECTICUT.

DUST CAP FOR LUBRICATION NIPPLES.

1,408,229.

Specification of Letters Patent. Patented Feb. 28, 1922.

Application filed October 21, 1920. Serial No. 418,410.

To all whom it may concern:

Be it known that I, BERNARD H. SKELLY, a citizen of the United States, residing at the city of Bridgeport, in the county of Fair-
field and State of Connecticut, have invented certain new and useful Improvements in Dust Caps for Lubrication Nipples; and I do declare the following to be a full, clear, and exact description of the invention, such 10 as will enable others skilled in the art to which it appertains to make and use the same.

This invention relates to certain new and useful improvements in dust caps for lubricating nipples or shackle bolts, and the primary object of the invention is to provide a smooth unbroken bore for the reception of a lubricant gun nozzle, and a dust cap structure which is held in position under tension 15 over said bore and which can be easily and quickly moved to open position and in the latter position positively held and disposed so as to permit the free and unobstructed use of a lubricant gun for the purpose of 20 supplying lubricant.

A still further object of the invention is to provide a construction wherein the parts are secured in position solely through frictional contact to thus necessitate a simple 25 and single driving operation in order to apply the entire device to the bolt.

Further and other objects will be later set forth and manifested.

In the drawings:

Figure 1 is a side elevation;
Figure 2 is a top plan view;

Figure 3 is an enlarged fragmentary sectional view, and

Figure 4 is an enlarged fragmentary sectional elevation of a lubricating nipple equipped with the improved dust cap.

I have shown my invention applied to both a shackle bolt and an ordinary lubricating nipple, but the construction of the 45 lubricant receiving element is substantially the same in both instances, and therefore the invention is not limited to adaptation to either of these specific forms of lubricant receiving elements.

Referring particularly to Figures 1, 2, and 50 3, wherein the invention is illustrated in connection with a shackle bolt 1, the latter is provided with the usual type of lubricating passage, the inlet to which latter is in

the form of a smooth, unbroken elongated bore 2 whose mouth is provided with a countersunk annular seat 3.

Within the bolt 1 and parallel with the bore 2 is a hole or socket 4, which latter is entirely without said bore and has no connection therewith.

A cap 5 is shaped to conformably rest in the seat 3 and is provided with a pair of spaced holes through which the legs of an approximately J-shaped piece of wire or rod 6 are extended so that a substantially U-shaped handle is provided. The shorter leg of the rod is riveted to the cap at 7, while the longer leg extends into the hole 4 and has an abutment 8 formed on its free 70 end. A coil spring 9 surrounds the longer leg of the J-shaped member 6 and at one end engages against the abutment, while its opposite end rests against the inner end of a sleeve 10, which latter has a driving fit 75 in the hole 4 and is received over the longer leg of the J-member.

It will now be seen that with the parts related as depicted in Figure 3, of the drawings, it is merely necessary to drive the sleeve 80 into the hole 4 wherein same is held by and through frictional contact and due to the fact that the only pressure exerted on the sleeve is that exerted by the light spring, there is no likelihood of the sleeve becoming displaced.

In operation the handle is grasped to move the cap and therewith the longer leg of the member 6 against the action of the spring, until the cap is free of its seat 3, whereupon the cap, with the longer leg as a pivot is swung to one side until the seat and consequently the lubricant inlet 2, are exposed. In this position, the cap is held stationarily by the spring which, upon release of the cap 95 expands and draws the cap against the bolt end in the position of Figure 1 of the drawings.

This dust cap structure may be applied to the lubrication nipples that are located at 100 various points on an automobile chassis, and at Figure 4 there is shown such an adaptation, 11 being the nipple having its inner end 12 threaded so that it may be driven into the bearing or part to be lubricated. 105 While the base 6 is quite serviceable, any suitable projection or knob 13 may be used instead, in which instance a straight pin 14

would extend loosely through the sleeve 10 into the hole 4 with a head 15 at the lower end, the spring 9 being confined and functioning as hereinbefore described, and this 5 pin would be secured at its upper end to the cap 5, all as shown at Figure 4.

The chief feature of this invention resides in the fact that the dust cap and the oil receiving chambers are admirably adapted for 10 use in connection with a lubricant supply gun, and the nozzle of the latter will fit snugly within the bore 2 since the latter has a smooth unbroken surface, while the dust cap can be lifted from its seat and swung 15 to one side, so as to leave the bore 2 clear for the unobstructed introduction of the oil gun nozzle.

What is claimed is:

The combination with a lubricating nipple having a smooth unbroken elongated 20 bore of uniform diameter which communicates directly with the lubricant passage of the nipple, the outer end of said bore having a countersunk seat, of a cap adapted to conformably rest within said seat, and a 25 spring tensioned pivotal support connected to the nipple outside said bore to which support said cap is secured, whereby the latter may be raised clear of the seat and swung to one side to permit of the introduction 30 within said bore of a lubricant delivery device.

In testimony whereof I affix my signature.
BERNARD H. SKELLY.
